MOBILE

Melvin Lyon, 57 5th St., Hoboken, N.J., and Oscar M. Gossett, R.F.D. 1, South Salem, N.Y.

Filed Aug. 28, 1959, Ser. No. 57,363

Term of patent 14 years

(Cl. D25—1)

Fig. 1 is a front elevational view of a mobile showing our new design; and

Fig. 2 is a bottom plan view thereof.

This application is a continuation-in-part of our co-pending application Serial No. D. 51,925, filed July 24, 1958, now abandoned.

We claim:

The ornamental design for a mobile, substantially as shown and described.
